RAILWAY TRAFFIC CONTROLLING APPARATUS

Henry S. Young, Wilkinsburg, Pa., assignor to
The Union Switch & Signal Company, Swiss-
vale, Pa., a corporation of Pennsylvania

Application September 4, 1943, Serial No. 501,254

13 Claims. (Cl. 246—3)

1

My invention relates to railway traffic controlling apparatus and more particularly to a centralized traffic control system for governing train movements over a single track railway, and is an improvement upon the system disclosed in my Letters Patent of the United States No. 2,326,991, issued August 17, 1943, for Railway traffic controlling apparatus.

My invention contemplates the provision of an absolute permissive block system comprising automatic signals for both directions at spaced points in each single track stretch with opposing headblock signals at each end for governing traffic movements into the stretch, all controlled over a reversible line circuit system employing but two line wires, together with other headblock signals for governing traffic movements into the passing tracks, the latter being controlled over separate line circuits for the two directions. The control of the signals in accordance with traffic conditions is effected by the provision of continuous track circuits for all main track, having track relays the contacts of which control the line circuits.

My invention also contemplates the provision of a communication system of the impulse code type, having a coding unit at each of a plurality of field stations located at the ends of the passing sidings for controlling the operation of the track switches from a distant point such as a train dispatcher's office, and for superimposing manual control upon the headblock signals and for governing the direction of traffic, the code system also serving to indicate the condition of the switches and signals and the movement of trains at the control office.

One object of my invention is the provision of an improved arrangement of electrically interlocked circuits at the control office governed by the control levers for those signals which govern train movements into the single track stretch, so as to prevent interference with train movements in the event of improper manipulation of these levers and to prevent the reversal of the direction of traffic except when the single track stretch is unoccupied.

Another object of my invention is the provision of an improved system of directional control in the field, involving the control of the reversible line circuit system for the signals for the single track stretch by directional stick relays at the opposite ends of the stretch, which relays are operated by control codes sent to both ends of the stretch to set up the desired traffic direc-

2

tion under the control of a master directional relay at the office.

Another feature of my invention relates to the control of a block indicator at the office to indicate when any portion of the single track stretch is occupied, which indicator is controlled jointly by codes transmitted from both ends of the single track block under the control of relays governed over the reversible line circuit system by which the signals are controlled, no additional line wires being needed.

Another object of my invention resides in the provision of improved arrangements for electrically locking all hand throw switches giving access to the main track in the territory covered by the system, including time controlled means for enabling the switch to be unlocked to permit a train to enter the side track, together with means subject to control by the central office operator for governing movements out of the side track, the remote control of the electric switch locks being attained by controlling the signal line circuits in a suitable manner.

Other objects, purposes and features of my invention will be pointed out as the description proceeds.

I shall describe one form of apparatus embodying my invention and shall then point out the novel features thereof in claims.

30 Referring to the accompanying drawings, Fig. 1 shows a portion of a suitable machine located at the control office and arranged for the control of one form of apparatus embodying my invention, including control panels for two field stations located at the opposite ends of a single track block as indicated by the miniature track diagram at the top of the view, while Figs. 2A, 2B and 2C show a plan of the corresponding stretch of railway track together with the trackway apparatus and circuits. More particularly, Figs. 2A and 2C show the apparatus at two field stations including circuits for the control of a power operated track switch and the opposing headblock signals which govern traffic movements into the adjoining single track and double track stretches. Fig. 2C also shows, at the right, the apparatus and circuits as provided for the control of an electric lock for a hand throw switch located in the main track of the double track portion of the system comprising the passing siding, while Fig. 2B shows typical circuits for the automatic block signals at spaced intermediate locations within the single track portion of the system, together with the apparatus and circuits as provided for the control of an electric lock for a hand throw

switch located in one of the single track sections.

It is to be understood that the system of my invention is made up of a number of unit portions each generally similar to the one shown in the drawings, and that the drawings are so arranged that the circuits extending to the right-hand margin of Fig. 2C match those extending from the left-hand margin of Fig. 2A, so that Figs. 2C and 2A, arranged end to end with Fig. 2A at the right, illustrate the track plan together with the apparatus and circuits for governing train movements through a passing siding, while Figs. 2A, 2B and 2C, when arranged end to end in that order illustrate the track plan for a single track block together with the apparatus and circuits for governing train movements from one passing siding to the next one.

Similar reference characters refer to similar parts in each of the several views.

The code system employed for communication between the office and stations is to be understood to be of the type shown in Letters Patent of the United States No. 2,229,249, issued January 21, 1941, to Lloyd V. Lewis, for Remote control systems, but modified in two particulars to correspond with the showing of the earlier Lewis patent, No. 2,197,130, issued April 16, 1940, these modifications comprising first, the provision of two additional steps in each control code, for the control respectively of a traffic direction controlling stick relay such as the relay 2RFS or 4LFS, and of another stick relay such as the relay 2WLS or 4WLS for the control of an electric switch lock, and second, the provision of arrangements to enable these relays as well as the usual switch control relays 1WS and 3WS, and the usual signal control relays 2LHS, 2RHS, 4LHS and 4RHS to be of the stick polar type, as shown, all of these relays being of the stay-where-put type, arranged to be held in their last operated positions when deenergized.

Any suitable remote control system other than the ones mentioned may also be used, a suitable system being shown, for example, in the pending application for Letters Patent of the United States, Serial No. 496,907, filed July 31, 1943, by Arthur P. Jackel, for Remote control systems.

Consideration of the detailed mode of operation of the code communication system is not needed for an understanding of my invention and it is deemed sufficient to point out that coding units are provided at the office and at each station which are connected by line wires Y-Z, as indicated diagrammatically in the drawings, over which control codes are transmitted at times from the office to a selected station, while at other times indication codes are transmitted over the same line wires from the different stations to the office without interference. Each code includes a distinctive code call by means of which a selector relay such as the relay 1S or 2S at the office, and a similar relay 1S or 2S at one station only is energized to effect the temporary establishment of a group of seven communication channels between the selected control panel at the office and the corresponding station to position a group of stick relays. The different stations have different code calls, consequently the selector relays for different stations or panels are not energized at the same time, the same channels providing communication at different times with all the stations. The channels employed in the transmission of a control code from the office to a selected station are represented herein by a group of wires 1 to 7, inclusive, while those em-

ployed in the transmission of an indication code from a station to the corresponding office panel are represented by another group of wires 9 to 15, inclusive.

Considering the station of Fig. 2A, for example, it is to be understood that the coding unit at that station includes a starting relay, not shown, which responds to a change in position of any of the indicating relays which provide connections from terminal B of the local source of current to the wires 9 to 15, as shown, and thereby effects the delivery of an indication code to the line Y-Z during which a selector relay 1S at the sending station and a delivery relay 03D at the office are temporarily energized in response to a distinctive code call to position a group of seven indication relays K in accordance with the condition of energization of the channels 9 to 15. The office indication relays governed from the station of Fig. 2A, for example, includes a track indication relay 1TK controlling an "OS" lamp 1TKE in the track diagram of Fig. 1 to indicate the condition of the track section 1T containing the power operated track switch 1W, relay 1TK being governed by a repeating relay 1TP of the track relay 1TR for the section; normal and reverse switch indication relays 1NWK and 1RWK controlling the lamps 1NE and 1RE associated with the control lever 1SW for switch 1W, and governed by the switch repeating relays 1NWP and 1RWP which indicate the position of switch 1W, provided such position corresponds with that of its control relay 1WS and operating relay 1WR; two signal indication relays 2LHK and 2RHK controlling the lamps 2LE, 2NE and 2RE associated with the control lever 2SIG for the signals 2RA, 2RB, 2LA and 2LB, and governed by relays 2LGP and 2RGP which repeat the stop indications of these signals; and two approach indication relays 2LBK and 2RBK controlling the lamps 2LBE and BKE to indicate block occupancy. Relays 2LBK and 2RBK are controlled by block repeating relays 2LBP and 2RBP which in turn are controlled jointly by line relays 2LHD and 2RHD which also control the entering head-block signals and by approach relays 2RAR and 2LAR in a novel manner as hereinafter described.

Those relays which control the channels 9 to 15 at the station of Fig. 2C function similarly to govern the indication relays K for the right-hand panel in Fig. 1, in response to indication codes including a different code call to which relays 3S and 03D are responsive, but in this case channel 14 is not used. It is to be understood that lamp 6LBE is controlled by a relay similar to 2LBK but associated with the next control panel to the right of those shown.

The block indication lamp BKE is governed by codes transmitted from both stations by relays 2RBP and 4LBP one of which indicates the condition of a portion of the single track block and the other that of the remainder.

The switch lever 1SW and the signal lever 2SIG of the left-hand panel of Fig. 1 are the usual switch and signal levers for the code control of the switch stick relay 1WS and the signal stick relays 2LHS and 2RHS at the station shown in Fig. 2A, while the levers 3SW and 4SIG of the right-hand panel control similar relays 3WS, 4LHS and 4RHS at the other field station, shown in Fig. 2C. The two signal levers 2SIG and 4SIG are electrically interlocked with respect to the control of train movements into the intervening single track stretch by the provision of a master directional stick relay 2-4LP as in

in my prior Patent No. 2,326,991, by means of which the desired traffic direction, designated by the operator by reversing one signal lever or the other, is selected automatically under the proper traffic conditions, as reflected by the block indication relays. Preferably the signal levers as well as the switch levers 1SW and 3SW are of the types mentioned in the Lewis Patent No. 2,229,249 and function generally as therein described. The push buttons 1STB and 3STB are the starting buttons for operating the usual code starting relays 1ST and 3ST by means of which control codes are initiated and the corresponding stations selected. For example, when the button 1STB is operated, the closing of its contact *a* completes a circuit from the positive or supply terminal B of a suitable local source of current through the winding of relay 1ST to the negative or common return terminal C of the same source, and relay 1ST picks up to establish a stick circuit extending to terminal B at the back contact *i* of a selector relay OIS, associated with the same panel. Relay 1ST when energized initiates a control code as described in Patent No. 2,229,249, including a code call for energizing relay OIS of the same panel. Relay OIS releases relay 1ST and connects terminal B to selected ones of the wires 1 to 7 in accordance with the positions of the control levers, and at the selected station, Fig. 2A a delivery relay 1D responds to the code call to effect the operation of the selected stick relays. Relay 1WS, for example, is operated to normal or reverse over channel 1 or 3 to correspond with the position of lever 1SW. The other stick relays are each operated to normal or reverse in accordance with the condition of energization of a single control channel, a series of intermediate register relays F being interposed as in Patent No. 2,197,130, in order that this may be accomplished. Relay 2LHS or 2RHS is operated to reverse when lever 2SIG occupies its left-hand or right-hand position so as to energize relay 1F5 or 1F7 over channel 5 or 7, respectively, relays 2LHS and 2RHS being operated by the code to their normal or left-hand position if lever 2SIG occupies its normal center position. The traffic direction relays 2RFS and 4LFS at the opposite ends of the block are controlled over channel 2 in accordance with the direction of traffic set up as indicated by the position of the directional stick relay 2-4LP above referred to.

As shown, the trackway circuits of Figs. 2A, 2B and 2C are set up for westbound traffic, that is to say, for train movements from right to left, as indicated by the lighting of the direction indicator lamp WFE of Fig. 1, with the left-hand contacts of relay 2-4LP closed, as shown. Accordingly, relay 2RFS is operated to the left by a code delivered by relay 1D when relay 1F2 is energized over channel 2, while relay 4LFS is operated to the left by a code delivered by relay 3D when relay 3F2 is not energized.

It is to be noted that the contacts of relays 2-4LP, 2RFS and 4LFS all point to the left for westbound traffic movements and to the right for eastbound traffic movements, that is to say, toward the exit end of the block, and that relays 2RFS and 4LFS are therefore operated in opposite directions in response to the energization of channel 2 to designate the exit end.

Since relays 2RFS and 4LFS are located at different stations, it will be evident that when the clearing of a signal involves the reversal of the direction of traffic, it requires the transmis-

sion of control codes to the stations at both ends of the single track block. The initiation of the two codes is accomplished automatically, however, by a single operation of but one of the two starting buttons 1STB or 3STB in accordance with a feature of my invention, with the aid of a pair of slow release stick relays EFK and WFK controlled by relay 2-4LP. These two relays are controlled over circuits corresponding to those for the similarly designated relays shown in an application for Letters Patent of the United States, Serial No. 412,279, filed September 25, 1941, by James J. Van Horn, for Railway traffic controlling apparatus, now Patent No. 2,344,333, granted March 14, 1944. In addition to controlling the code transmission these relays also serve as direction locking relays. It is to be understood that normally, the position of relay 2-4LP can be changed only when the block is vacant as manifested by the energized condition of the two block indication relays 2RBK and 4LBK. This indication is cancelled locally with the aid of relays WFK and EFK, so that lamp EKE becomes lighted when the position of relay 2-4LP is changed, and remains lighted until new indications are received, indicating that the block is vacant with the trackway system set up for the new traffic direction. During this interval relays WFK and EFK are both released and their back contacts *c* bridge the contacts *e* of the block indication relays in the circuit for relay 2-4LP, so that relay 2-4LP is free to be operated to either position. This is desirable because it permits the operator to restore the original traffic direction if, due to a fault, the desired reversal cannot be effected.

Assuming, for example, that a block clear indication has been received following the establishment of the right to left direction, as shown, relay WFK is picked up over a circuit extending from terminal B at the left-hand contact *d* of relay 2-4LP, back contact *b* of relay EFK, front contacts *c* of relays 2RBK and 4LBK through the winding of relay WFK to terminal C, and is then held energized over a stick circuit including its own front contact *a* extending directly to terminal B at contact *d* of relay 2-4LP. If relay 2-4LP is now operated to the right to reverse the traffic direction, the opening of its left-hand contacts *b* and *d* causes the release of relays 2RBK, 4LBK and WFK, the latter relay being slow to release and consequently holding its back contact *d* open for a time sufficient to insure the release of relays 2RBK and 4LBK. Relay WFK remains released along with relay EFK until new block clear indications are received from both stations. If button 1STB is now operated, the closing of its contact *a* causes relay 1ST to pick up to initiate a control code for operating relay 2RFS to the right, and relay 3ST will be operated over contact *b* of button 1STB and back contacts *g* of relays EFK and WFK to initiate a control code for operating relay 4LFS to the right. The same result may be attained by operating button 3STB, as will be clear from the drawing.

Levers 2SL and 4SL are three-position levers for electric switch lock control and govern the polar stick relays 2WLS and 4WLS over channel 4. Lever 2SL normally occupies its normal center position as shown, and is operated to the left or right to set up the corresponding traffic direction for a movement from a side track to the main line over a hand throw switch located in the single track stretch, such as the

switch 2W shown in Fig. 2B, lever 2SL controlling the reversible line circuit system in such a manner as to permit the train crew to release the electric lock 2WL provided the entire block is unoccupied. Lever 2SL is preferably of the push-turn type, such as is shown in Letters Patent of the United States No. 2,289,736, granted July 14, 1942, to Clarence S. Snavely and Regis H. Zetwo, for Circuit controllers. It is to be understood that lever 2SL is restrained against rotation from one position to another by a detent which is released when the lever is pressed to close auxiliary contacts *a* and *b*. These contacts when closed complete the circuits for relays 1ST and 3ST, and it follows that each operation of the rotary contacts *c*, *d* and *e* of lever 2SL from one position to another results in the delivery of codes to the stations at the two ends of the block within which switch 2W is located.

Lever 4SL, associated with the right-hand panel, is of the same type as lever 2SL, and the momentary closing of its contact *a* in response to the rotation of its contact *c* from one position to another serves to initiate the transmission of a control code to operate relay 4WLS of Fig. 2C over channel 4, to govern the movement of a train from a side track to the main track of the adjacent passing siding over an electrically locked hand throw switch located in the block governed by signal 4RA or 2LA, such as the switch 4W in the right-hand portion of Fig. 2C.

Circuits for governing the control code channel 6 are not shown, as this is used for purposes having no bearing on my invention, such as for the control of a maintainer's call signal, for example.

The directional relay 2-4LP is controlled generally in the same manner as in my prior Patent No. 2,326,991 except for the auxiliary circuit provided by relays WFK and EFK, and for such modifications as are brought about by the addition of lever 2SL. That is to say, relay 2-4LP may be operated to the position shown by moving lever 4S1G or 2SL to the left, or to the reverse position by moving lever 2S1G or 2SL to the right, provided the indication relays indicate that the block is clear and that the head-block signals governing traffic movements into the block are at stop, as shown. The circuits for relay 2-4LP extend from terminal B at back contact *b* of relay 3TK, back contact *d* of relay 4LHK, front contacts *e* of relays 4LBK and 2RBK, back contacts *d* and *b* respectively, of relays 2RHK and 1TK, normal contacts *e* and *d* of lever 2SL to contacts *b* of levers 2S1G and 4S1G. By moving lever 4S1G or 2SL to the left, the circuit is extended from contact *b* of lever 4S1G or the left-hand contact *d* of lever 2SL over the center or left-hand contact *a* of lever 2S1G through the lower winding of relay 2-4LP to terminal C, to operate the relay to the left, as shown. With lever 4S1G normal, or to the right, the movement of lever 2S1G or 2SL to the right extends the circuit from contact *b* of lever 2S1G or from the right-hand contact *e* of lever 2SL over the center or right-hand contact *a* of lever 4S1G through the upper winding of relay 2-4LP to terminal C, to reverse the relay.

In response to a change in position of relay 2-4LP, relays 2RBK and 4LBK release, but the circuits for relay 2-4LP are maintained available so that the relay may be restored to its original position if desired by the provision of a branch connection including the back contacts *c* of relays EFK and WFK, as already explained.

Considering now the trackway apparatus of Figs. 2A, 2B and 2C, it is to be understood that each of the signals is of the well-known search-light type and has a three-position mechanism such as that shown in Reissued Letters Patent of the United States of E. J. Blake No. 14,940, dated August 31, 1920, each such mechanism being identified by the general reference character G prefixed by the designation of the corresponding signal shown symbolically in the track plan in the upper portion of these views. Each main line signal mechanism such as 4LAG or 21G controls a repeating relay such as 4LAPC or 21PC. Each signal repeating relay is energized when the signal indicates caution or proceed as indicated by the closing of the corresponding front contact Y or G of its mechanism, except when the length of the block section in advance of the signal is less than that required to stop a high speed train. In the latter case, as illustrated by signals 2LA and 4RA, the signal repeating relay is energized only when the signal indicates proceed. Each signal repeating relay serves when energized to supply current of normal polarity to the line circuit for the next signal in the rear governing traffic in the same direction, to cause such signal to indicate proceed, as illustrated, for example, by signal 23 as shown. Each automatic signal, as shown in Fig. 2B, is provided with the usual directional stick relay such as 21SR which picks up when a train passes the signal at caution or proceed, which serves when energized to supply current of reverse polarity to the next signal in the rear for the control of a following train. The headblock signals of Figs. 2A and 2C are normally lighted by suitable lamps, not shown, while the automatic signals are normally dark and lighted only upon the approach of a train, by the release of an approach relay such as the relay 21AR, which relay jointly with relay 22PC for the opposing signal 22, controls lamp 21E for signal 21, as shown.

Time locking for preventing the operation of the track switches 1W and 3W except under proper traffic conditions, and for electrically interlocking the opposing headblock signals which govern traffic movements into the same block, is obtained by the provision of approach locking stick relays such as the relays 4RAS and 4LAS controlled jointly by indicating relays such as the relay 4RGP for signals 4RA and 4RB and relay 4LGP for signals 4LA and 4LB, and by the corresponding signal control relays 4RHS and 4LHS. The arrangement is such that the clearing of the signal 4RA, for example, is made dependent upon the release of the approach locking relay 4RAS which it controls, the latter relay having a back contact *c* in the circuit for mechanism 4RAG for signal 4RA. In response to the reversal of the signal control relay 4RHS, a block repeating or route relay 4BPR becomes energized, provided traffic conditions at the time are such as to make it proper for the signal 4RA to be cleared, that is, provided the route governed by signal 4RA is available. With relay 4RHS reversed, the opening of back contact *b* of relay 4BPR causes relay 4RAS to release, and the closing of the front contact *b* of relay 4BPR and of the back contact *c* of relay 4RAS then completes the circuit for energizing mechanism 4RAG.

Each approach locking relay is reenergized automatically in the usual manner in response to the release of the track relay for the section directly in advance of the associated signal, and

also when a signal is manually put to stop, by the operation of a time element relay such as the relay 3TER controlled by relay 4ASP. Relay 4ASP also provides a distinctive indication at the office of the operation of relay 3TER. When relay 4ASP is picked up it initiates an indication code in which channels 13 and 15 are both connected to terminal B over its contacts *b* and *c*, thereby energizing the office indication relays 4LHK and 4RHK to extinguish lamp 4NE without lighting either lamp 4LE or 4RE. The indication lamps associated with the signal lever therefore remain dark until relay 3TER completes its operation to pick up the associated approach locking relay, whereupon relay 4ASP is released to transmit an indication code to again light lamp 4NE.

Each of the track switches such as 3W governing movements into or out of the passing siding is operated by a switch machine such as 3SM controlled by a polar neutral switch operating relay 3WR in the normal manner, each such relay being controlled by the associated code controlled relay such as 3WS over a circuit including front contacts of the approach locking relays such as 4RAS and 4LAS, and of the detector track relay 3TR.

Front contacts of the last named relays are also included in the connection to terminal C in the circuits for relay 3WS, rendering relay 3WS non-responsive to a control code except under conditions which permit operation of the track switch. The circuits for the signal control relays such as 4LHS and 4RHS have a back contact *c* of the associated time element relay 3TER included in the connection to terminal C, the provision of this contact serving to prevent the release of the approach locking relay 4RAS or 4LAS and its subsequent reenergization by relay 3TER unless relay 3TER starts its operation from its normal position so as to consume a predetermined time in closing its front contacts.

Considering now the hand throw switches 2W and 4W, it is to be understood that each such switch is provided with a suitable hand throw switch stand, such for example, as is shown in Letters Patent of the United States No. 2,184,870, issued December 26, 1939, to Herbert L. Bone and Kenneth J. J. McGowan, and that its operation is governed electrically by the provision of an electric switch lock controlled by a lock magnet such as 2WL, the electric switch lock being preferably of the type shown in Letters Patent of the United States No. 1,126,834, issued February 2, 1915, to Walter P. Neubert and William E. Smith. For an understanding of the present invention it is believed that it will suffice to point out that the operating lever 8 of the switch stand is normally locked mechanically in a position to maintain the track switch locked normal by a lever latch attached to a segment 25 which is held in locking position by the bail 50 of a padlock as indicated diagrammatically in Fig. 2B of the accompanying drawings and as shown in detail in Fig. 1 of the Neubert et al. patent. To unlock the switch, the padlock must first be removed by the train crew to permit the segment 25 to be moved a short distance to a position to engage the locking dog 27 and to close contacts 46-47, and to also open contact 49 to release an indicating relay such as 2WLP. Then if traffic conditions as reflected by the circuits are such as to indicate that it is proper to unlock the switch, the lock magnet 2WL will become energized to open contact 48 and to lift the locking dog 27,

permitting segment 25 to be moved to its full reverse position in which the switch operating lever 8 is free to be operated, the segment being held reversed mechanically as explained in the 5 Neubert et al. patent until lever 8 is again restored to normal. It is also to be understood that the switch stand is equipped with the usual switch circuit controller and point detector having a contact N which is closed only when the 10 switch is locked normal.

For movements into the side track, no cooperation with the central office operator is required, a circuit for energizing the lock magnet 2WL being prepared by the operation of a time element relay 2TER which is set into operation when a train enters the track section 22T in which the switch 2W is located. For movements out of the side track, the energization of two line relays WAR and EAR is required in order to obtain an unlock, these relays being controlled over the signal line circuit in response to the movement of the lever 2SL to the left or right as hereinafter described.

The mechanism and circuits for controlling switch 4W are generally similar to those for switch 2W as above described, except that the lock magnet 4WL is controlled over the signal line circuits from a source of current at the station of Fig. 2C, movements into the side track being governed by the operation of a time element relay 4TER, and movements out of the side track by a locking relay 4WLSR controlled by lever 4SL.

The circuits for the control of electric switch locks as shown herein are an improvement upon those disclosed in an application for Letters Patent of the United States Serial No. 462,354, filed October 17, 1942, by Harvey A. Haines, for Railway traffic controlling apparatus, now Patent No. 4,236,723, issued January 23, 1945.

Considering now the reversible line circuit system for the single track stretch, the circuits as shown are set up for westbound traffic, but with the head block signals at stop. The first section of the line circuit system corresponds with the block section extending from its exit end to signal 21 and provides a circuit for controlling that signal which may be traced from terminal B at the station of Fig. 2A through the winding of relay 2LAR, back contact *b* of relay 2LAPC, front contact *f* of relay 2RAS, normal polar contact *b* of relay 2RFS, front contacts *b* of the track relays 1TR and 2RT for sections 1T and 2RT, line wire 29, front contact *b* of the track relay 21TR for section 21T, back contacts *b* of relays 22PC and 22SR through mechanism 21G and thence over contact *c* of relay 22SR, contacts *a* of relays 22PC and 21TR, line wire 28, contacts *a* of relays 2RTR, 1TR and 2RFS, contact *e* of relay 2RAS and contact *a* of relay 2LAPC to terminal C of the same source. Mechanism 21G is therefore energized in the reverse direction so that signal 21 indicates caution as shown, and relay 2LAR is also energized, indicating that the corresponding block section is clear, and completing a circuit from terminal B over the left-hand contact *c* of relay 2WLS and front contact *a* of relay 2LAR through relay 2RBP to terminal C. Since relay 2RBP is energized, it may be assumed that a code has been transmitted from the station of Fig. 2A to pick up relay 2RBK of Fig. 1, which relay as shown is held energized over a stick circuit extending from terminal B at the left-hand contact *b* of relay 2-4LP, back contact *d* of relay EFK, front con-

tact *a* of relay 2RBK, back contact *f* of relay 01D through the winding of relay 2RBK to terminal C.

In Fig. 2B, relay 21PC is energized over front contact *Y* of mechanism 21G to complete the second section of the line circuit system corresponding to the block section extending from signal 21 to signal 23 and providing a circuit for controlling signal 23, which extends from terminal B of the source at the location of signals 21 and 22 over the back contacts of mechanism 22B, relay 21AR, front contact *c* of relay 21TR, front contacts *a* of relays 21PC and 22TR, line wire 39, front contacts *a* and *b* of relay 2WLP, line wire 32, front contact *a* of relay 23TR, back contacts *a* of relays 24PC and 24SR, through mechanism 23G, thence over contacts *b* of relays 24SR, 24PC and 23TR, line wire 33, contacts *d* and *c* of relay 2WLP, line wire 31, and contacts *b* of relays 22TR and 21PC to terminal C. Mechanism 23G is energized in the normal direction to cause signal 23 to indicate proceed, and relay 21AR is also energized, becoming released to light lamp 21E in response to the release of the track relay 23T or 22T by a train approaching signal 21.

Relay 23PC is energized over the front contact *G* of mechanism 23G to complete the third section of the line circuit system corresponding to the block section extending from signal 23 to signal 4LA and providing a circuit for relay 4LHD which may be traced from terminal B of the source at the location of signals 23 and 24 over the back contacts of mechanism 24G, relay 23AR, contact *c* of relay 23TR, contacts *a* of relays 23PC and 24TR, line wire 34, front contacts *a* of relays 4LTR and 3TR, the normal polar contact *a* of relay 4LFS, the winding of relay 4LHD and thence over contacts *b* of relays 4LFS, 3TR and 4LTR, line wire 35, and contacts *b* of relays 24TR and 23PC to terminal C.

Relay 23AR is therefore energized becoming released to light lamp 23E in response to the release of the track relay 3TR, 4LTR or 24TR by a train approaching signal 23, and relay 4LHD is energized in the normal direction, completing a circuit over its front contact *a* and normal polar contact *d* to energize relay 4LBP. It may be assumed therefore that a code has been transmitted from the station of Fig. 2C to pick up relay 4LBK of Fig. 1, which relay as shown is held energized over a stick circuit similar to that for relay 2RBK as above traced, the block indication lamp BKE being extinguished when relays 2RBK and 4LBK are both energized as shown.

It will be seen that when the line circuit system is set up for westbound traffic as shown, the energization of relay 2RBK indicates that the block section extending from signal 2RA to signal 21 is clear, and that the energization of relay 4LBK indicates that the two block sections extending from signal 21 to signal 23, and from signal 23 to signal 4LA, respectively, are both clear, consequently these relays when both energized indicate that the entire block from signal 2RA to 4LA is clear.

I shall now assume that the operator desires to clear signal 4LA to admit a westbound train to the single track block, with the apparatus initially in the condition shown in the drawings. The operator will move lever 4SIG to its left-hand position and press button 3STB, thereby energizing relay 3ST to initiate the transmission of a control code to the station of Fig. 2C in which channel 5 is energized over the left-hand

contacts *d* of relay 2-4LP and of lever 4SIG, operating relay 4LHS to reverse.

The approach locking relay 4LAS associated with signal 4LA is normally held energized over a stick circuit extending from terminal B at the left-hand contact *a* of relay 4LHS, front contact *b* of relay 4LGP and the front contact *a* and winding of relay 4LAS to terminal C.

When relay 4LHS reverses, the energization of this circuit is shifted to its right-hand contact *a* to include back contact *a* of the block repeating relay 4BPR, but since relay 4LHD is energized, relay 4BPR now picks up over the circuit extending from terminal B at the left-hand contact *b* of relay 4RHS over contacts *b* of relays 4LHS and 4LHD, contacts *a* of relays 3RWP and 3NWP, contact *d* of relay 3TP through relay 4BPR to terminal C. Relay 4BPR opens its back contact *a* to release relay 4LAS, thereby completing a circuit for mechanism 4LAG extending from terminal B at the right-hand contact *a* of relay 4LHS over front contact *a* of relay 4BPR, front contact *c* of relay 4RAS, back contact *c* of relay 4LAS, contact *f* of relay 4LHD, front contact *c* of relay 3NWP, mechanism 4LAG, back contact *c* of relay 3RWP, contacts *e* and *c* of relay 4LHD, and contacts *c* of relays 4LHS and 4RHS to terminal C, mechanism 4LAG being thereby energized in the normal direction to cause signal 4LA to indicate proceed, and also energizing relay 4LAPC, and releasing relay 4LGP. The release of relay 4LGP initiates the transmission of an indication code to energize the office indication relay 4LHK, thereby extinguishing lamp 4NE and lighting lamp 4LE. The opening of back contact *d* of relay 4LHK opens the circuit for relay 2-4LP and the opening of back contact *e* of relay 4LHK renders lever 2SL incapable of controlling relays 4LFS and 2WLS, thereby maintaining the westbound traffic direction.

Assuming next that the train passes signal 4LA at clear, the release of the track relay 3TR releases relays 3TP, 4LHD and 23AR, lighting lamp 23E to cause the signal 23 in advance to indicate proceed. Relay 3TR also closes a circuit momentarily at its back contact *f* to restore relay 4LHS to normal. Relays 4LBP and 4BPR, mechanism 4LAG, and relay 4LAPC also release, relay 4LGP becoming reenergized to complete a pick-up circuit for relay 4LAS at back contact *e* of relay 3TR so that relay 4LAS becomes reenergized. An indication code is now transmitted to energize the office indication relays 3NWK and 3TK and to release relays 4LBK and 4LHK, consequently lamps 3TKE, BKE and 4NE become lighted and lamp 4LE is extinguished.

When the train passes signal 23 at clear, the closing of back contact *d* of relay 23TR completes a pick-up circuit for relay 23SR, which, when section 24T is vacated, supplies current of reverse polarity to the line wires 34 and 35 over its contacts *b* and *c*, energizing relay 4LHD in the reverse direction and thereby conditioning signal 4LA to indicate caution in response to the reversal of relay 4LHS by another control code.

In the event the operator desires to clear signal 4LB instead of signal 4LA, he will reverse lever 2SW, move lever 4SIG to the left and then press button 3STB, transmitting a code to reverse relays 3WS and 4LHS. The circuit for relay 4NWP includes a normal polar contact *c* of relay 3WS and relay 3NWP releases quickly in response to the reversal of relay 3WS, and prevents relay 4BPR from picking up, consequently

relay 4LAS remains energized and relay 3WR becomes energized in the reverse direction to operate switch 3W to reverse. Relay 3RWP picks up when the switch becomes locked in its reverse position and by closing its front contact *a* completes the circuit for relay 4BPR which then picks up to release relay 4RAS.

With relay 4LHS reversed and relays 4BPR and 3RWP energized, the closing of back contact *c* of relay 4LAS completes the circuit for mechanism 4RBG over front contact *c* of relay 3RWP to clear signal 4LB.

I shall next assume that the apparatus has been restored to the condition shown and that the operator desires to reverse the direction of traffic and to clear signal 2RA to admit an eastbound train to the single track block. The operator will move lever 2SIG to its right-hand position, completing a circuit at the lever contact *b* to reverse relay 2-4LP, which releases relays 2RHK, 4LBK and WFK as already described, and thereby extinguishes lamp WFE and lights lamps EFE and BKE, and he will then press button 1STB momentarily resulting in the energization of both of the starting relays 1ST and 3ST to send two successive control codes, one to each station. In the code sent to the station of Fig. 2A, channel 2 is deenergized and channels 1 and 7 are energized, causing relays 2RFS and 2RHS to reverse while in the code sent to the station of Fig. 2C, channels 1 and 2 are energized and relay 4LFS reverses. It may be that the operator also moves lever 4SIG to the right to clear the leaving signal 4RA by the same code, as is permissible.

The reversal of relay 2RFS disconnects the adjacent current source from the reversible line circuit system and connects relay 2RHD thereto, causing the deenergization of the tandem connected line circuits governing westbound traffic thereby releasing relays 2LAR and 2RBP, mechanism 21G, relays 21PC and 21AR; mechanism 23G, and relays 23PC, 23AR, 4LHD and 4LBP. The reversal of relay 4LFS disconnects relay 4LHD from the line circuit system and connects terminals B and C of the source at the station of Fig. 2C thereto through the winding of relay 4RAR to initiate the energization of the tandem connected line circuits governing eastbound traffic, thereby causing relays 4BAR, 4LBP, mechanism 24G, relays 24PC and 24AR, mechanism 22G, and relays 22PC, 22AR, 2RHD and 2RBP to become energized over circuits for governing eastbound traffic similar to the circuits for governing westbound traffic already traced. Signal 2RA then clears as the result of operations similar to those involved in the clearing of signal 4LA as already described. More particularly, when relay 2RHD picks up it completes the circuit for relay 2BPR at its front contact *b*, since relay 2RHS stands reversed, and relay 2BPR picks up, opening its back contact *b* to release relay 2RAS to complete a circuit for energizing mechanism 2RAG in the normal direction to cause signal 2RA to indicate proceed, and to energize relay 2RAPC and to release relay 2RGP.

When relay 4LBP picks up, an indication code will be transmitted from the station of Fig. 2C to energize the office indication relay 4LBK. An indication code will also be transmitted from the station of Fig. 2A to energize relays 2RHK and 2RHK, thereby energizing relay EFK and extinguishing lamps BKE and 2NE, and lighting lamp 2RE and locking relay 2-4LP reversed.

It will be noted that relay 4LBP is controlled by relays 4LHD and 4RHR and relay

2LBP by the relays 2LHD and 2RAR in such a manner that the condition of the intermediate block section which extends from signal 22 to signal 23 is indicated by relay 4LBP when westbound traffic is set up and by relay 2RBP when eastbound traffic is set up. That is to say, the indicating relay at the entering end indicates the condition of two of the three block sections and the one at the leaving end indicates the condition of the third block section.

After the eastbound traffic direction has been set up as described, the operator may restore signal 2RA manually to stop by transmitting the proper control code and may then reverse the traffic direction to clear signal 4LA by operations similar to those required when westbound traffic is already set up. However, if signal 2RA, for example, is put manually to stop, the reenergization of relay 2RAS is delayed for a suitable time interval to protect against an improper change in traffic conditions in advance of a train approaching at high speed.

Assuming that mechanism 2RAG is energized, with section 1T unoccupied, relays 2RGP and 2RAS will be in the released position, and if relay 2RHS is restored to normal by the operator, mechanism 2RAG releases and relay 2RGP picks up. Relay 2ASP becomes energized over the circuit extending from terminal B at contact *a* of relay 2RHS, contact *b* of relay 2RGP, back contact *a* of relay 2RAS, contact *e* of relay 1TP, relay 2ASP, and the left-hand contacts *c* of relays 2RHS and 2LHS to terminal C. Relay 1TER is energized over contact *a* of relay 2ASP. The closing of contacts *b* and *c* of relay 2ASP initiates an indication code, energizing channels 13 and 15 to pick up relays 2LHK and 2RHK to extinguish lamp 2RE, but without lighting lamp 2NE or 2LE. After a predetermined time interval relay 1TER closes its front contacts *a* and *b*, contact *a* completing the circuit for relay 2RAS which picks up, releasing relay 2ASP to initiate a second indication code to release relays 2LHK and 2RHK and light lamp 2NE again.

I shall next assume that a westbound train passes from the single track block to section 2LT, and that the operator desires to clear signal 2RB for an eastbound train standing on the side track at the left of section 1T. The operator will move lever 2SIG to the right as for clearing signal 2RA as above described but in addition will reverse lever 1SW before pressing button 1STB. In this case in the code sent to the station of Fig. 2A channels 3 and 7 are energized and channel 2 deenergized so that relays 1WS, 2RFS and 2RHS reverse and a code is also sent to the station of Fig. 2C to reverse relay 4LFS, the operation of relays 2RFS and 4LFS reversing the line circuit system to set it up for eastbound traffic as already described. The reversal of relay 1WS releases relay 1NWP, preventing relay 2BPR from picking up, the circuit for relay 2BPR being open also at front contact *b* of relay 2RHD until the reversal of the line circuit system is consummated, and relay 2RAS remains picked up, relay 1WR becoming energized in the reverse direction to operate switch 1W to reverse. Relay 1RWP picks up when the switch becomes locked in its reverse position, relay 2BPR becoming energized to release relay 2RAS to effect the energization of mechanism 2RBG for clearing signal 2RB in response to the energization of relays 1RWP and 2RHD, in this instance.

It will be clear that the reversal of traffic direction is effected automatically, that is to say,

without special manipulation by the operator, the operations involved in setting up eastbound traffic and clearing signal 2RA or 2RB being similar to those involved in clearing signal 4LA or 4LB when westbound traffic is already set up.

It may be that the operator will desire to reverse the traffic direction without clearing the entering signal for the new direction. To set up eastbound traffic, for example, without clearing signal 2RA or 2RB, all that is necessary is to move lever 2SIG to the right to reverse relay 2-4LP, and to then restore it to its normal center position before pressing button 1STB, as will be readily apparent.

Considering now the line circuit system which extends the length of the passing track, and placing Fig. 2A at the right of Fig. 2C, it will be seen that relay 2LHD is energized, with its polar contacts reversed, over a circuit extending from terminal B, Fig. 2C, at front contact *a* of relay 4RTR over back contact *b* of relay 4LAPC, contact *f* of relay 4RAS, contact *b* of relay 3TP, back contact *f* of relay 4WLSR, front contact *b* of relay 4TEP, line wire 31, contact *b* of relay 4WLP, line wire 41, contact *b* of relay 2LTR, relay 2LHD, contact *a* of relay 2LTR, line wire 40, contact *a* of relay 4WLP, line wire 36, contact *a* of relay 4TEP, contact *e* of relay 4WLSR, contact *a* of relay 3TP, contact *e* of relay 4RAS, contact *a* of relay 4LAPC, and contact *b* of relay 4RTR to terminal C, contacts *a* and *b* of relay 3TP and contacts *e* and *f* of relay 4RAS in the circuit as traced being bridged by contacts *e* and *f* of relay 3RWP when switch 3W is reversed.

Relay 4RHD is energized, with its polar contacts reversed, in series with relay 2RAR over a circuit extending from terminal B, Fig. 2A, through the winding of relay 2RAR, back contact *b* of relay 2RAPC, contact *f* of relay 2LAS, contact *b* of relay 1TP, contact *d* of relay 2LTR, line wire 43, contact *d* of relay 4WLP, line wire 39, back contact *d* of relay 4WLSR, back contact *c* of relay 4TER, contacts *d* of relays 4TEP and 4RTR, the winding of relay 4RHD, contacts *c* of relays 4RTR and 4TEP, contact *b* of relay 4TER, contact *c* of relay 4WLSR, line wire 38, front contact *c* of relay 4WLP, line wire 42, contact *c* of relay 2LTR, contact *a* of relay 1TP, contact *e* of relay 2LAS, and back contact *a* of relay 2RAPC to terminal C, contacts *a* and *b* of relay 1TP and contacts *e* and *f* of relay 2LAS in the circuit as traced being bridged by contacts *e* and *f* of relay 1RWP when switch 1W is reversed.

It will be seen that the energization of relay 2LHD indicates that sections 4RT and 2LT are unoccupied, and that section 3T is unoccupied or switch 3 is reversed, while the energization of relays 4RHD and 2RAR indicates that sections 4RT and 2LT are unoccupied, and that section 1T is unoccupied or switch 1 is reversed. Consequently, the energization of relay 2LBP, as controlled by relays 2RAR and 2LHD, indicates that sections 4RT and 2LT are unoccupied, as required for the control of the office indication relay 2LBK governed by relay 2LBP, relay 2LBK controlling lamp 2LBE of the track diagram.

I shall now assume that the operator desires to clear signal 2LA to admit a westbound train to the block which extends to signal 4RA when switch 3W is normal, and to the next signal in advance for the same direction, namely, to signal 4LA when switch 3W is reversed. The operator will move lever 2SIG to its left-hand position and press button 1STB, thereby energizing relay 1ST to initiate the transmission of a con-

trol code to the station of Fig. 2A to operate relay 2LHS to reverse.

When relay 2LHS reverses, the stick circuit for relay 2LAS is shifted from the left-hand to the right-hand contact *a* of relay 2LHS, and if section 1T is vacant and the line relay 2LHD is energized in the reverse direction, as shown, relay 2BPR becomes energized over the circuit including contacts *b* of relays 2RHS, 2LHS and 2LHD, back contact *a* of relay 1RWP, front contact *a* of relay 1NWP, contact *d* of relay 1TP through relay 2BPR to terminal C. By opening its back contact *a*, relay 2BPR releases relay 2LAS, which completes a circuit for mechanism 2LAG extending from terminal B at the right-hand contact *a* of relay 2LHS, front contact *a* of relay 2BPR, contacts *c* of relays 2RAS and 2LAS, contact *b* of relay 1NWP, contact *f* of relay 2LHD, mechanism 2LAG, contacts *e* and *c* of relay 2LHD, and the right-hand contact *c* of relay 2LHS to terminal C. Mechanism 2LAG is therefore energized reverse to cause signal 2LA to indicate caution, releasing relay 2LGP. If, now, signal 4LA is cleared so as to energize relay 4LAPC, relay 2LHD will become energized in the normal direction and will shift its polar contacts to cause signal 2LA to indicate proceed, energizing relay 2LAPC to reverse the polarity of the current supplied to the next signal 21 in the rear, causing signal 21 to indicate proceed. It is assumed that the distance from signal 2LA to signal 4LA is less than that required to stop a high speed train, and consequently signal 21 is arranged to indicate proceed only if signal 2LA also indicates proceed.

I shall next assume that the operator desires to clear signal 2LB to admit a westbound train to the upper passing track. The operator will reverse lever 1SW, move lever 2SIG to its left-hand position and then press button 1STB, to initiate a code for operating relays 1WS and 2LHS to reverse. Relay 2BPR is prevented from picking up by the release of relay 1NWP by relay 1WS as in the prior examples, and when switch 1W becomes locked reverse in response to the reversal of relay 1WS, relay 1RWP picks up. If section 1T is unoccupied, relay 2BPR then becomes energized over the circuit including front contacts *a* and *g* of relay 1RWP and front contact *d* of relay 1TP, and releases relay 2LAS to complete a circuit at its back contact *c* over contact *b* of relay 1RWP to operate mechanism 2LBG to reverse to cause signal 2LB to indicate caution.

Signals 4RA and 4RB may be controlled in a similar manner by the operation of levers 3SW and 4SIG, as will be readily apparent from the drawings.

Considering now the operation of the hand throw switch 2W, by reference to Fig. 2B it will be seen that when a train enters the track section 22T containing the switch 2W, the dropping of the track relay 22TR completes a circuit over the line wires 44 and 45 extending from the location of the track relay at signal 22 to the location of switch 2W, to initiate the operation of a time element relay 2TER. The line circuits for signals 2RA and 4LA include front contacts *a*, *b*, *c* and *d* of a switch repeating relay 2WLP which is normally energized over a local circuit extending from terminal B over contacts 48 and 49 of the electric switch lock, back contact *b* of relay 2TER and contact N controlled by switch 2W through relay 2WLP to terminal C, which circuit is broken by relay 2TER when it starts its oper-

ation and serves to check that relay 2TER starts its operation from its normal position to measure a predetermined time before closing its front contact *a*, which time is of the order of several minutes and serves to prevent the unlocking of the switch in advance of an approaching high speed train. The crew of a train which consumes this time in section 22T and stops at switch 2W may unlock the switch by removing padlock 50 and closing contacts 46-47 to pick up the lock magnet 2WL over the circuit having a connection to terminal B at contact *a* of relay 2TER. Signals 22, 23, 2RA, 2RB, 4LA and 4LB are held at stop, their line circuits being held open by relay 2TR until the train clears the main line, and by relay 2WLP until switch 2W is again locked normal.

To enable a train to enter the main line via switch 2W, the central office operator in response to a telephone call from the train crew will move lever 2SL to the left or right according to the direction the train is to move after entering the single track stretch, provided the entire block is unoccupied, and the entering signals are at stop. This results in the energization of relay 2-4LP over the left-hand contact *d* or the right-hand contact *e* of lever 2SL to operate relay 2-4LP to a position corresponding to that of lever 2SL, and the momentary closing of contacts *a* and *b* of lever 2SL initiates two control codes, one to the station of Fig. 2A in which channel 4 is energized over the connection to terminal B including the lever contacts *c* and back contacts *e* of relays 2RHK and 4LHK and contact *h* of relay O1S, to reverse relay 2WLS, and the other to the station of Fig. 2C in which channel 2 is energized irrespective of the position of relay 2-4LP, over contact *h* of relay O3S, to reverse relay 4LFS. The eastbound traffic direction will be set up in the portion of the line circuit system at the right of switch 2W by the reversal of relay 4LFS and the westbound traffic direction in the portion to the left of switch 2W, due to the closing of the right-hand contacts *a* and *b* of relay 2WLS, as will be apparent from the drawings and the opening of contact *c* of relay 2WLS will deenergize relay 2RBP to effect the delivery of an indication code to release relay 2RBK and thereby light lamp BKE.

Under these conditions the release of relay 2WLP by the train crew results in the energization of relays WAR and EAR, provided the respective block portions extending to signals 2RA and 4LA are unoccupied, with the left-hand portion of the line circuit system set up for westbound traffic and the right-hand for eastbound traffic, permitting magnet 2WL to be energized to unlock the switch over the connection to terminal B including the front contacts *a* of relays WAR and EAR.

After the unlock has been obtained, the central office operator will restore lever 2SL to its normal center position, closing the lever contacts *a* and *b* momentarily, resulting in the delivery of control codes to restore relay 2WLS to normal and to operate relays 2RFS and 4LFS to a position to correspond with that of relay 2-4LP as indicated by lamp WFE or EFE. If the train is westbound, for example, signal 21 will indicate caution or clear and relay 21SR will become energized to cause signal 23 to indicate caution when the train vacates section 22T, permitting signal 4LA to be cleared for a following train providing switch 2W has been locked normal to energize relay 2WLP.

It will be apparent that other hand throw switches equipped like switch 2W may be located in any of the single track sections for operation in the manner described and that only one lever 2SL is required regardless of their number or location within the single track block.

It will also be clear that the purpose of using a three-position lever such as 2SL for switch control is to provide means for positioning relay 2-4SL to correspond with the desired direction of traffic movements in the single track block following the restoration of the lever to normal, so as to restore the absolute permissive block system to its normal mode of operation as soon as the train passes the first intermediate signal in advance of the hand throw switch by which it entered the block. For the sake of uniformity in manipulation, a similar three-position lever 4SL is used for controlling switch 4W, although a two-position lever could be used in this instance.

Referring now to Fig. 2C, it will be seen that when a train enters the track section 4RT containing the hand throw switch 4W, the dropping of the track relay 4RTR for that section completes a local circuit at its back contacts *a* and *b* to initiate the operation of a time element relay 4TER. The line circuits for controlling the entering signals 4RA and 2LA for the double track block include front contacts *a*, *b*, *c* and *d* of a repeating relay 4TEP which is normally energized over a back contact *a* of relay 4TER and the circuit for relay 4RHD also includes back contacts *b* and *c* of relay 4TER. This arrangement serves to check the operation of relay 4TER, that is to say, to insure that relay 4TER starts its operation from its normal position to measure a predetermined time before closing its front contacts *b* and *c*, relay 4TER functioning like relay 2TER to prevent the unlocking of the switch in advance of an approaching high speed train. The crew of a train which consumes this time in section 4RT and stops at switch 4W may unlock the switch by removing its padlock 50 and opening contact 49 to release relay 4WLP, thereby energizing the lock magnet 4WL over the circuit extending from terminal B at front contact *c* of relay 4TER, back contact *d* of relay 4WLSR, line wire 39, back contact *d* of relay 4WLP, magnet 4WL, contacts 46-47, back contact *c* of relay 4WLP, line wire 38, back contact *c* of relay 4WLSR and front contact *b* of relay 4TER to terminal C. Signals 4RA and 2LA are held at stop, their line circuits being held open by relay 4RTR until the train clears the main line, and by relay 4WLP until switch 4W is again locked normal.

To enable a train to enter the main line via switch 4W, the central office operator will move lever 4SL to the left or right, the momentary closing of the lever contact *a* causing the delivery of a control code to the station of Fig. 2C in which channel 4 is energized over contact *c* of lever 4SL and contact *k* of relay O3S to reverse relay 4WLS. If the block is vacant and signal 2LA is at stop with relay 2LAS energized or switch 1W reversed, relay 4RHD will be energized, and if signal 4RA is also at stop with relay 4RAS energized or switch 3 reversed, a circuit will be completed from terminal B at the reverse contact *a* of relay 4WLS over front contact *a* of relay 4RHD and over front contacts *g* of relays 4RAS and 3TP or over contact *h* of relay 3RWP through relay 4WLSR to terminal C. Relay 4WLSR therefore picks up if conditions are proper for unlocking the switch, and is held energized over a stick cir-

cuit including its own front contact *a* and the reverse contact *a* of relay 4WLS. Contacts *c*, *d*, *e* and *f* of relay 4WLSR open the line circuits for relays 4RHD and 2LHD, and terminal B of the source at the station of Fig. 2C which is connected over back contact *b* of relay 4LAPC to contact *f* of relay 4WLSR becomes connected through resistor 20 and front contact *d* of relay 4WLSR to line wire 43 and thence over back contact *b* of relay 2RAPC through relay 2RAR to terminal B of the source at the station of Fig. 2A, while terminals C of these two sources are connected together over back contacts *a* of relays 4LAPC and 2RAPC, front contacts *c* and *e* of relay 4WLSR and line wire 42. Relay 2RAR consequently releases, releasing relay 2LBP to initiate an indication code for energizing relay 2LBK and thereby lighting lamp 2LBE in the track diagram.

When relay 4WLSR is picked up, the release of relay 4WLP by the train crew permits magnet 4WL to be energized to unlock the switch over the circuit extending from terminal B at front contact *a* of relay 4RTR, back contact *b* of relay 4LAPC and thence over front contacts *f* and *d* of relay 4WLSR and resistor 20, line wire 39, back contact *d* of relay 4WLP, magnet 4WL, contacts 46-41, contact *c* of relay 4WLP, line wire 33, front contacts *c* and *e* of relay 4WLSR and thence to terminal C at front contact *b* of relay 4RTR.

After the unlock has been obtained, the operator will restore lever 4SL to its normal center position thereby initiating a control code for restoring relay 4WLS to normal to release relay 4WLSR, the system becoming restored to its normal condition when switch 4W is locked normal with relay 4WLP energized. It will be evident that other hand throw switches equipped like switch 4W may be located in any of the sections of the block extending from signal 4RA to signal 2LA and that only one lever 4SL is required for their control.

Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

1. In combination with a stretch of single track railway divided into block sections, signals for governing traffic movements in opposite directions into the stretch, a system of reversible circuits for controlling the signals; a line relay, an approach relay, a block relay and a traffic direction relay at each end of the stretch; means controlled by the traffic direction relays in corresponding positions for reversibly connecting a source of current to said system of circuits at one end in series with the associated approach relay and for connecting the line relay at the other end thereto to energize said approach relay when the adjacent block section is unoccupied and to distinctively energize said line relay only when the remaining block sections are unoccupied, means controlled by each line relay when distinctively energized for clearing the adjacent signal, and means for energizing each block relay when the adjacent approach relay is energized and also when the adjacent line relay is distinctively energized, and indication means controlled jointly by said block relays to indicate when the entire stretch is unoccupied.

2. In combination with a stretch of single track railway divided into block sections, signals for governing traffic movements in opposite directions into the stretch, a system of reversible circuits for controlling the signals; a line relay, an approach relay, a block relay and a traffic direction relay, at each end of the stretch; a master directional relay at a distant control office, means for operating both traffic direction relays to positions corresponding to that of said master directional relay, means controlled by the traffic direction relays in corresponding positions for reversibly connecting a source of current to said system of circuits at one end in series with the associated approach relay and for connecting the line relay at the other end thereto to energize said approach relay when the adjacent block section is unoccupied and to distinctively energize said line relay only when the remaining block sections are unoccupied, means controlled by each line relay when distinctively energized for clearing the adjacent signal, means for energizing each block relay when the adjacent approach relay is energized and also when the adjacent line relay is distinctively energized, and means preventing the operation of said master directional relay from one position to another except when both of said block relays are energized.

3. In combination with a stretch of single track railway divided into block sections, signals for governing traffic movements in opposite directions into the stretch, a system of reversible circuits for controlling the signals; a line relay, an approach relay, a block relay and a traffic direction relay at each end of the stretch; a master directional relay at a distant control office, means for operating both traffic direction relays to positions corresponding with that of said master directional relay, means controlled by the traffic direction relays in corresponding positions for reversibly connecting a source of current to said system of circuits at one end in series with the associated approach relay and for connecting the line relay at the other end thereto to simultaneously energize the approach relay at one end and the line relay at the other end of the stretch when the two block sections at opposite ends of the stretch are unoccupied, means effective when the portion of the block between said end sections is unoccupied for supplying current of a distinctive character to said line relay, means controlled by each line relay for controlling the adjacent signal, means for energizing each block relay when the adjacent approach relay is energized and also when the adjacent line relay is energized by current of said distinctive character, indication relays at said office for repeating the condition of said block relays, and means controlled by said indication relays for controlling said master directional relay.

4. In combination with a stretch of railway track having a signal at each end for governing the movement of traffic into the stretch, a line relay, a traffic direction relay and a signal control relay at each end of the stretch; a signal lever for each signal, two stick relays, a directional relay, and block indication means all located at a control office; circuits controlled by said traffic direction relays in one position for energizing the line relay at one end of the stretch, circuits controlled by said traffic direction relays in another position for energizing the line relay at the other end of the stretch, means governed by traffic conditions in said stretch for controlling said block indication means to indicate

when the stretch is unoccupied, pick-up and stick circuits for one stick relay closed by the directional relay in one position and for the other stick relay closed by the directional relay in its other position, said pick-up circuits including contacts closed only when the block indication means indicates that the stretch is unoccupied, means for locally actuating said block indication means to open said contacts whereby one stick relay is released when the position of the directional relay is changed and the other does not become energized until the block indication means is again governed by traffic conditions to indicate that the stretch is unoccupied, a circuit controlled by each signal lever when reversed for operating the corresponding signal control relay, a circuit controlled by each signal lever effective if one signal lever or the other is reversed either when said block indication means indicates that the stretch is unoccupied or when both stick relays are released to actuate said directional relay to a position corresponding to the desired direction of traffic movement through the stretch, means controlled by said directional relay for operating both traffic direction relays to positions in which the circuits they control are conditioned to effect the energization of that line relay which is associated with the operated signal control relay, and means controlled by such line relay and signal control relay for clearing the adjacent signal.

5. In combination with a stretch of railway track having a signal at each end for governing the movement of traffic into the stretch, a traffic direction relay at each end of the stretch, a signal control relay for each signal, circuits for said signals controlled jointly by both traffic direction relays for controlling the direction of traffic movements into the stretch to permit the clearing of either signal in response to the operation of its signal control relay; a signal lever for each signal, a directional relay, signal indication means controlled by the signals and block indication means controlled by traffic conditions in said stretch all located at a control office, circuits for operating said directional relay to one position when one signal lever is reversed and to another position when the other signal lever is reversed, effective only when the signal indication means indicates that the signals are at stop, and initially effective only when the block indication means indicates that the stretch is unoccupied, circuits controlled by said directional relay for operating both traffic direction relays to positions in which the circuits they control are conditioned to set up the desired direction for traffic movements, means for maintaining the circuits for said directional relay effective after its position has been changed, regardless of the condition of said block indication means, said maintaining means being effective only until the block indication means is again operated in accordance with traffic conditions to indicate that the stretch is unoccupied, and a circuit controlled by each signal lever when reversed and by the directional relay in a corresponding position for energizing the associated signal control relay.

6. Railway traffic controlling apparatus comprising a signal at each end of a stretch of single track railway for governing the movement of traffic into the stretch, a group of code controlled relays including a traffic direction relay and a signal control relay at each end of the stretch, a system of reversible signal circuits controlled jointly by the traffic direction relays in corre-

sponding positions which reflect the condition of occupancy of said stretch to render one signal or the other responsive to the operation of its control relay, code controlled indication means at a control office for indicating the condition of said circuit system and of said signals, a signal lever for each signal, and a directional relay at said office, circuits for operating the directional relay to one position or another in response to the reversal of one signal lever or the other effective when the indication means indicates that the stretch is unoccupied, provided neither signal has been cleared, a starting button for each signal lever, a code transmitter adapted to initiate the transmission of a code to one end of the stretch or the other in response to the operation of one button or the other, each such code including elements controlled by the signal lever associated with the operated button for operating the control relay for the signal which such lever controls to a position corresponding with that of its lever and for operating the traffic direction relay associated therewith to a position corresponding with that of the directional relay, direction locking means effective when released to render the operation of either button effective to initiate the transmission of such codes to both ends of the stretch, means for releasing said locking means in response to a change in the position of the directional relay, and means for maintaining said locking means released until new indications are received to indicate the reversal of said signal circuit system by said traffic direction relays in response to such codes.

35 7. Railway traffic controlling apparatus comprising a signal at each end of a stretch of single track railway, a code controlled traffic direction relay at each end of the stretch for governing the direction of traffic movements through the stretch; a signal lever for each signal, a directional relay operable to one position by one signal lever and to another position by the other signal lever for selecting the desired direction of traffic movements through the stretch, block indication means which indicates when the traffic direction indicated by said directional relay is established and a code transmitter, all located at a control office; a starting button for each signal lever, means responsive to the operation of each button to initiate the delivery of a code by said transmitter to the corresponding end of the stretch for controlling the signal at that end in accordance with the position of its lever and for also controlling the associated traffic direction relay in accordance with the position of such directional relay, and means responsive to a change in the position of said directional relay for rendering each starting button temporarily effective to initiate the transmission of such codes to both ends of the stretch, said last named means remaining effective only until said block indication means is actuated to indicate that the traffic direction has been reversed in response to the operation of the traffic direction relays by such codes.

8. Railway traffic controlling apparatus comprising a signal at each end of a stretch of single track railway, two code controlled traffic direction relays, one at each end of the stretch, for governing the direction of traffic movements through the stretch; a signal lever for each signal, direction selecting means controllable by said levers, for governing the operation of said traffic direction relays and a code transmitter, all located at a control office; a starting button for

each signal lever, starting means responsive to the operation of each button for initiating the delivery of a code by said transmitter to the corresponding end of the stretch for controlling the signal at that end in accordance with the position of its lever and for also controlling the associated traffic direction relay in accordance with the condition of said direction selecting means, and means governed by said direction selecting means and acting only when the direction selected thereby is changed to render the starting means controlled by each button temporarily responsive to the operation of the other button, whereby the operation of either button to initiate the transmission of a code to one end of the stretch is automatically effective if such button is operated when the stretch is unoccupied and the desired traffic direction is not set up to initiate the delivery of a second code by said transmitter for controlling the traffic direction relay at the other end of the stretch.

9. Railway traffic controlling apparatus comprising a signal at each end of a stretch of single track railway, a code controlled traffic direction relay at each end of the stretch a system of circuits controlled by said traffic direction relays for controlling the signals in accordance with traffic conditions in the stretch and for controlling the direction of traffic movements through the stretch; a signal lever for each signal and a code transmitter located at a control office; a starting button for each signal lever, starting means responsive to the operation of each button occurring when the associated signal lever is reversed and the required traffic direction is already set up for initiating the delivery of a code by said transmitter to the corresponding end of the stretch, each such code including elements for controlling the signal and traffic direction relay at that end, and means acting automatically if the lever for either signal is reversed when the opposing traffic direction is set up but the stretch is unoccupied and the opposing signal is at stop for initiating the delivery of codes by said transmitter to both ends of the stretch in response to a single operation of the starting button associated with such lever, said codes serving to position the traffic direction relays as required to reverse the traffic direction and to clear the signal governed by the reversed signal lever.

10. In combination with a section of railway track including a hand throw switch, an electric lock for preventing the hand operation of the switch, a track relay for said section, an indication relay adjacent the switch having an energizing circuit closed only when the switch is locked in its normal position, a signal for governing the movement of traffic into said section, a time element relay adjacent the signal, an energizing circuit for the signal including line wires extending from the signal location to the location of the switch and including contacts controlled by the time element relay and closed in its normal position, and also including front contacts of said track relay and of said indication relay, means responsive to the release of said track relay for initiating the operation of said time element relay whenever a train enters said track section, means adjacent the switch for manually releasing said indication relay, and a circuit for energizing said electric lock to unlock the switch including back contacts of said indication relay, said line wires and contacts closed by the time element relay a predetermined time after its operation is initiated.

11. In combination with a section of railway track including a hand throw switch, an electric lock for preventing the hand operation of the switch, an indication relay adjacent the switch having an energizing circuit closed only when the switch is locked in its normal position, a signal for governing traffic movements into said section, a line circuit for controlling the signal including contacts closed only when the section is unoccupied and said indication relay is energized, a switch control relay adjacent the signal, a stick relay, a pick-up circuit for said stick relay including a contact of said control relay, a contact which when closed indicates that the signal is at stop, and a contact closed only when the line circuit for said signal is energized, a stick circuit for said stick relay including its own front contact and said control relay contact, and a circuit for energizing said electric lock to unlock the switch including back contacts of said indication relay and front contacts of said stick relay.

12. In combination with a stretch of single track railway having signals for governing traffic movements in both directions through the stretch, a hand throw switch located in said stretch, an electric lock for preventing the hand operation of the switch, a reversible line circuit system for controlling said signals, a directional relay at a control office for controlling the direction of energization of said line circuit system to govern the direction of traffic movements through the stretch, a three-position switch lever having a normal position and two reverse positions corresponding to the two directions of traffic movement through the stretch, means responsive to the movement of said lever to either reverse position to prepare a circuit for energizing the electric lock to permit the unlocking of the switch and for also operating the directional relay to a position corresponding with that of said lever, and means rendered effective upon the restoration of said lever to its normal position for conditioning said line circuit system for train movements in a direction corresponding to the operated position of said directional relay.

13. In combination with a stretch of single track railway, a hand throw track switch located in said stretch, an electric lock for preventing the hand operation of the switch, an indication relay adjacent the switch having an energizing circuit closed only when the switch is locked in its normal position, signals for governing traffic movements in both directions through the stretch, a reversible line circuit system for controlling said signals and extending the length of the stretch, the portion adjacent said switch including front contacts of said indication relay, a directional relay at a control office for controlling the direction of energization of said line circuit system to thereby govern the direction of traffic movements through the stretch, a three-position switch control lever having a normal center position and two reverse positions corresponding to the two directions of traffic movements through the stretch, means responsive to the movement of said lever to either reverse position for operating the directional relay to a corresponding position and for completing circuits including said line circuit system and back contacts of said indication relay to permit the energization of said electric lock to unlock the switch, and means rendered effective upon the restoration of said lever to its normal position with said indication relay again energized for conditioning said line circuit system for train movements in a direction corre-

sponding to the operated position of said directional relay.
